APPARATUS FOR CLEANING ROLLS

Charles F. Smith, Cicero, Ill., assignor to Rapid
Roller Co., Chicago, Ill., a corporation of Illinois

Application December 13, 1937, Serial No. 179,469

9 Claims. (Cl. 15—4)

The present invention relates in general to improved means for mechanically cleansing rolls such as the inking rolls utilized in printing, and the apparatus embodies a construction such as to enable the practice of a novel cleansing method, to the end that the rolls may be rehabilitated and used again.

Rolls such as utilized in printing may be constructed of different materials, for example, rubber, synthetic materials, vulcanized oil and glue-glycerine composition. These rolls are accurately finished within relatively close limits to predetermined diameters, and are provided with a highly polished surface for taking the ink.

Heretofore, the only cleaning method which could be safely used without injury to the roll was to simply wash the roll by hand with a cleaning fluid. Since the rolls have a high affinity for ink, the hand cleaning of the rolls was objectionable in that it was difficult if not impossible to clean them thoroughly by hand. Also, the various inks utilized caused the rolls to become sticky and tacky. Such a condition could not be eliminated by the usual hand washing method.

Another condition of the roll which could not be corrected by the hand washing method was due to the glazing which formed on the roll due to its use. The only way the glaze could be removed was by a grinding or polishing operation on the roll surface. Such a procedure was manifestly injurious to the roll, and in order to restore the roll, it became necessary to remove an amount of the roll material each time it was ground or polished. With repeated treatments of this nature, the roll became smaller and smaller until reduced to such size that it was beyond the roll adjustments of the press and had to be discarded.

The herein described invention proposes to overcome the difficulties and objections inherent in the foregoing methods of cleaning inking rolls by providing improved apparatus of such construction as to enable the practice of an entirely new method, whereby a roll may be thoroughly cleaned and rehabilitated, without injury, to the same condition as when new.

A further object of the invention is to provide apparatus for thoroughly cleaning the roll and restoring it to its original condition without in any way injuring the roll surface or decreasing its diameter, whereby the life of the roll is materially increased.

A further object of the herein described invention is to provide apparatus for cleaning a roll, which is of such construction that any ink which

penetrates the roll or has been absorbed during use will be brought to the surface during the cleaning operation and washed off, leaving the surface as smooth and velvety as originally, and with as great affinity for the ink as when the roll was now.

A still further object of the invention is to provide roll cleaning apparatus of such construction that a plurality of different cleaning operations may be carried on simultaneously.

Another object of the herein described invention is to provide roll cleaning apparatus wherein my novel cleaning process may be carried out quickly and automatically without the aid of expensive skilled labor.

In accordance with the general features of the invention, it is proposed to provide a chuck and adjustable tailstock arrangement by means of which the roll to be cleaned may be supported and rotated about its longitudinal axis. Adjacent to the roll thus mounted is an adjustable carriage arranged to be fed along the roll. This carriage has mounted thereon a pair of spaced idler rollers adapted to engage the roll surface as it is being rotated. One of these rollers is provided with a curved surface so that it will have a kneading action as it rolls over the roll surface. This kneading action of the roller will cause any ink which has penetrated or been absorbed by the roll material to come to the surface of the roll.

Disposed between the spaced rollers is a buffing disc of felt material which is arranged to buff the surface of the roll after it has been kneaded by the kneading roller. Simultaneously with the buffing operation, a stream of cleaning fluid or solvent is played on the roll surface. Thus, any ink which has been brought to the surface or may be disposed on the surface of the roll is acted upon by the cleaning fluid and buffed off by means of the buffing wheel.

Following the buffing operation as the carriage is moved along the roll, the other roller, which is termed a "squeeze roller" is passed over the surface of the roll. This roller is shaped to have a frusto-conical or tapered surface. The action of this roller is to squeeze out the ink and cleaning fluid remaining on the roll, and leaves the surface clean and velvety.

The carriage, in addition to being arranged for longitudinal feed along the roll, is also arranged to permit its adjustment in a direction at right angles to the feed movement, so that the kneading and squeeze rollers, together with the buffing wheel, may be moved towards and away from

the roll being cleaned, thus enabling the cleaning of rolls of different diameters.

Other objects and features of the present invention will more fully appear from the detailed description taken in connection with the accompanying drawings which illustrate a single embodiment thereof, and in which:

Figure 1 is a fragmentary elevational view of apparatus embodying the features of the herein described invention, parts being cut away to show the cooperative relationship of certain of the parts of the apparatus;

Figure 2 is a plan view of the same;

Figure 3 is an enlarged section through the apparatus showing the operative relationship between the cleaning instrumentalities and the roll, and also the arrangement for supplying cleaning fluid to the roll during cleaning operation, taken substantially on line III-III of Figure 1;

Figure 4 is an enlarged fragmentary view partly in section to show the engagement of the various cleaning instrumentalities with the roll, and the manner in which the roll surface is affected thereby, taken substantially on the line IV-IV of Figure 3;

Figure 5 is a detail fragmentary sectional view, taken substantially on line V-V of Figure 3, to show the manner in which the carriage is mounted for sliding adjustment towards and away from the roll being cleaned; and

Figure 6 is a detail view in section, taken substantially on line VI-VI of Figure 3, to show the mechanism for clutching and unclutching the carriage relative to its feed screw.

As shown on the drawings:

In general, the apparatus embodies a framework, roll supporting structure, a carriage with the cleaning instrumentalities operatively mounted thereon, a carriage feeding mechanism, cleaning fluid supply system and power means for operating the apparatus.

The frame structure comprises spaced end frames 10 and 11 which are rearwardly interconnected at their upper ends by means of an angle member 12. In the present instance, this angle member is integrally formed with the end frames. However, the angle member may be separately fabricated and have its ends secured in any appropriate manner to the end frames.

Forwardly disposed of the angle member 12 is a main guide rail 13 of circular cross section having its ends respectively connected and supported in the end frames 10 and 11.

The end frames are each forwardly extended at their upper ends to form confronting substantially semi-circular wall portions 14 and 15, the curved edges of these extensions being disposed downwardly and provided with inwardly extending arcuate peripheral flanges 16 and 17 respectively along their curved edges.

The wall portions 14 and 15 form a supporting structure for means whereby the roll to be cleaned may be rotatably supported. For this purpose, the extension walls 14 and 15 are interconnected by means of a pair of horizontally spaced guide rails 18 and 19 having their ends secured in the wall extensions. These rails are in parallel relation and have slidably mounted thereon an adjustable tailstock generally indicated at 20.

This tailstock is of the usual construction containing a spindle 21 which supports a dead center 22. The spindle is longitudinally adjustable by means of the usual hand wheel 23. The tailstock

may be secured in adjusted position on the guide rails or ways 18 and 19 by means of a set screw as shown at 24.

Associated with the wall extension 14, there is 5 rotatably supported in a suitable bearing 24 a chuck 25 which is arranged to be driven by means of a stepped driving pulley as shown at 26.

For driving the chuck, the stepped pulley 26 is connected through a belt 27 to a stepped pulley 10 28 which is interconnected and rotatably supported with a pulley 29 and sprocket wheel 30 upon a dead countershaft or spindle 31 supported on the end frame 10. The pulley 29 is in turn connected through a belt 32 to a driving pulley 33 on the drive shaft of an electric motor or other power means 34. This motor is supported on a suitable bracket 35 affixed to the end frame 10.

As shown in Figures 1 and 2, the ink roll to be cleaned comprises a cylindrical body 36 which

20 may be constructed of rubber, synthetic material, vulcanized oil, or other materials such as commonly employed in rollers of this type. The cylindrical body is mounted upon a centrally disposed elongate axle 37 having its end portions 25 projecting beyond the ends of the roll body. The inherent construction of the roll admits of its being easily supported in cleaning position. This is accomplished simply by supporting one end of the axle in the chuck, this end being gripped by the chuck jaws, while the other end is rotatably supported at its center on the tailstock center 22. With this arrangement the roll may be readily rotated in a manner similar to the workpiece in a lathe.

35 Secured to the top of the angular rail 12 is an elongate base plate 38 which cooperates with the guide rail 13 to form guide ways for a carriage 39 supported thereon for sliding movement on the ways between the end frames 10 and 11.

Adjustably supported on the carriage for movement in a direction at right angles to the direction of movement of the carriage along the ways 13 and 38 is a frame 40. This frame, as shown in Figure 5, is provided with a tongue portion 41 45 which disposed in and slidably associated with a groove 42. A screw 43 is rotatably connected at one end to the frame 40 and is in threaded engagement with a nut 44 which is integrally formed with the carriage 39. This screw may be 50 actuated by means of a hand wheel 45 at its other end. By rotating the screw 43, the frame 40 may be adjustably shifted transversely of the carriage 39.

The end of the frame 40 which is opposite the 55 end thereof that is connected to the screw 43 is shaped to form a combination hood 46 and support for the various cleaning instrumentalities.

The hood 46 is formed by spaced side walls 47 and 48 of generally sector shape, the curved edges of the walls being joined and interconnected by a curved wall 49. Referring to Figure 3, it will be noted that this housing opens toward the ink roll supported in position to be cleaned.

Supported substantially at the center of the 65 housing or hood 46 is a spindle 50 having its ends rotatably supported in suitable bearings 51 and 52 respectively formed in the side walls 47 and 48 of the hood. The spindle 50 extends through a sleeve 53 inside the hood, this sleeve having one end abutting the inside of wall 47, and its other end formed with an abutment flange 54 which abuts the wall 48 of the hood. This sleeve is secured to the spindle in any appropriate manner and for this purpose a set screw 55 may be provided.

Intermediate the ends of the sleeve, the sleeve is threaded externally as shown at 56 for association with a nut 57. The nut 57 and flange 54 serve as clamping members by means of which a plurality of buffing discs 58 of felt or other suitable material may be clamped therebetween for rotation with the sleeve 53.

With the arrangement just described, the buffing discs and sleeve 53 form a buffing wheel which may readily be removed as a unit from the hood housing, simply by loosening the set screw 55. With the set screw 55 loosened, the spindle 50 may be withdrawn from its bearing supports and from the sleeve 53, whereupon the buffing wheel may readily be removed from the hood for replacing the buffing discs or for any other reason.

The walls 47 and 48 of the hood are respectively provided with oppositely extending stub shafts 59 and 60. These stub shafts extend outwardly from the walls to which they are secured. The shaft 59 has rotatably supported thereon a roller 61 having a transversely curved peripheral surface, as shown. The shaft 60 supports a roller 62 having a frusto-conical surface. The roller is disposed on the shaft 60 with its larger end outermost. The rollers may be retained on their respective shafts in any desired manner. For this purpose it has been found convenient to provide the shaft with inwardly disposed abutment shoulders and secure the roller against removal from the shaft by means of a washer 63 disposed between the outer end of the roller and a cotter key 64 extending through the end of the shaft.

By reference to Figure 4, it will be observed that the size of the rollers 61, 62, and the buffer wheel 58 are so chosen in relation to their centers of rotation, that these elements may all engage the cylindrical body 36 of the printing roll 30 and act thereon simultaneously in a manner which will subsequently be described in detail.

One end of the spindle 50 is provided with a sprocket wheel 65 which is connected through a chain drive 66 to a sprocket wheel 67 mounted on the driving shaft of an electric motor or other power means 68. The motor 68 is supported on the frame 40, and, of course, will be movable with the frame during any adjustment thereof on the carriage 39.

The carriage is arranged to be automatically fed along the ways 13 and 38. For this purpose, a feed screw 69 is supported for rotative movement in the end frames 10 and 11, and as shown in Figure 3 extends through a portion of the carriage frame 39. The screw does not, however, make threaded engagement with the carriage where it extends therethrough. Means will subsequently be described for establishing connection between the carriage and the feed screw.

The feed screw is provided at one end with a sprocket wheel 70 which is connected by means of a chain 71 to the sprocket wheel 39 on the countershaft 31.

In order to permit a more rapid adjustment of the carriage along its ways, independently of the feed screw, a clutch generally indicated at 72 is provided for making clutched and unclutched connection between the carriage and the feed screw.

As shown in detail in Figure 6, there is provided in connection with the carriage a cylindrical housing 73 which defines a socket 74 for receiving a spring 75 therein. This spring surrounds a rod 76 which is supported for longitudinal shifting movement. This rod is supported

5 at one end of the housing by means of a plug 77 screwed into the open end of the housing socket, and at the other end the rod is provided with an end portion 78 of square cross section which is disposed in a square opening 79 in the bottom end of the housing. The juncture of the square portion 78 with the round portion of the rod defines an abutment shoulder 80 against which a washer 81 is pressed by virtue of its being engaged by one end of the spring. The other end 10 of this spring engages the plug 77. The square portion 78 terminates at its outer end in a sector nut 82 which is normally actuated by the spring 75 into engagement with the threads of the feed screw 69. The outer end of the rod 76 has swivelly mounted thereon a hand wheel 83 by means of which the rod may be longitudinally moved in such direction as to carry the sector nut 82 out of threaded engagement with the threads of the feed screw. The hand wheel carries a projecting lug 84 which is movable therewith and extends substantially parallel to the axis of the rod 76. The outer end of the lug 84 is adapted to be moved into and out of a suitable aperture disposed in the plug 77. Thus, when the sector nut 82 is disengaged from the feed screw, the hand wheel 83 may be rotated to move the lug 84 to a position wherein its outer end will abut the outer surface of plug 77 and hold the rod 76 against longitudinal movement to carry the sector nut into meshed relation with the feed screw. However, when it is desired to engage the sector nut with the feed screw, the hand wheel 83 may be rotated to a position wherein the lug may pass into its aperture in the plug 77 thus enabling movement of the rod under the influence of spring 75 to force the sector nut into meshed engagement with the feed screw.

20 By means of the clutch just described, the carriage may be released when desired for free movement on its ways independently of the feed screw. On the other hand, when the carriage is in desired position, the clutch may be actuated to bring the sector nut into engagement with the feed screw and by operating the feed screw the carriage will be fed automatically along its ways. During the cleaning of a roll by means of my improved method, a cleaning fluid is applied to the roll. This fluid may constitute any mixture which is not injurious to the roll material. For example, mixtures which have been successfully used comprise kerosene and naptha, water and caustics, and benzene and carbon tetrachloride.

25 A tank 85 for the cleaning fluid is supported on a depending frame structure 86, this frame structure being connected to and movable with the carriage 39. Supported on the frame structure and having its inlet connected with the tank 85, is a suitable pump 87.

The outlet side of the pump is connected to a conduit 88 which conducts the fluid to a nozzle 89 where it may be discharged between the buffer wheel and the roll.

30 In order that the fluid utilized in the cleaning operation may be returned to the tank 85 and used over again, a catch basin is provided below the roll and the cleaning instrumentalities. This tank is formed by a metal sheet 90 which is of arcuate form. The sheet 90 is supported at its ends on the flanges 16 and 17 of the wall extensions 14 and 15. The walls 14 and 15 provide ends for the catch basin, and it is preferable to make a fluid tight joint between the sheet 90 and the end walls. Hingedly con-

nected to the outermost edge of the sheet 80 is a hinged cover 91 which may be swingably moved to a position extending over the roll and cleaning instrumentalities or may be swung to the position shown in dotted lines in Figure 3 to afford ready access to the roll and permit its being easily removed and put into the device.

The cleaning fluid is returned through a conduit 92 having one end connected to the bottom of the catch basin, and its other end connected to the tank. At the point where the conduit 92 connects with the tank 85, it is desirable to provide a suitable filter as generally shown in dotted lines at 93, for cleaning the fluid before it re-enters the tank.

Although the pump 87 may, if desired, be driven by a separate electric motor or power means, in the present instance the pump is shown as being provided with a driving pulley 94 which is connected through a belt 95 to a drive pulley 96 on the drive shaft of the motor 68. Intermediate the pulleys 94 and 96, the belt 95 may be trained over a pair of guide pulleys 97 and 98 which form a part of a belt tensioning device.

Since the supply conduit for the cleaning fluid is rigidly supported adjacent its nozzle end on the hood 46 by means of a bracket 99, it will be evident that the nozzle 89 will be moved with the hood as the carriage moves along its ways during the cleaning operation. Moreover, since the tank 85 moves with the carriage and the outlet conduit 92 is connected to the drain basin, it will be appreciated that the supply and return conduits 88 and 92 respectively should be provided with flexible sections to permit free movement of the carriage and the frame 40 of the carriage structure.

The operation and method of my invention will now be described.

The roll which is to be cleaned is supported in the chuck and tailstock as shown in Figure 2. The rollers 61 and 62, and the buffing wheel 58 are then adjusted by means of the hand wheel 45 until the rollers are pressing into the roll cylinder and the buffing wheel is just in engagement with the surface of the roll cylinder. Having determined the proper adjustment of the cleaning instrumentalities with reference to the cylinder roll, the carriage is moved so that the roll 61 will start its operation at the extreme end, in this instance the right end of the roll when the cleaning operation is begun. The motors 34 and 68 may then be started, and as soon as liquid is flowing from the nozzle 89, the clutch 72 may be actuated to connect the carriage to the automatic feed screw 69.

With the motors running, the roll will be rotated and the buffing wheel revolved. As the carriage moves along to carry the cleaning instrumentalities along the roll cylinder, the roll 61, which will be rotated by virtue of the rotation of the cylinder roll, will operate to knead the roll material and cause any ink which has penetrated the same or which has been absorbed to be brought to the surface.

Following the kneading action of the roller 61, the buffer wheel will buff the surface of the roll cylinder and coat with the cleaning solution to remove any ink which may be thereon.

Following the buffing operation, the roller 62 moves over the roll surface and acts to squeeze out any remaining fluid thereon and dry the surface. This roller is also revolved by virtue of its engagement with the roll cylinder.

The foregoing steps of my improved method

are automatically carried out in definite order as the cleaning of the roll progresses. The cleaning operation does not in any way injure the roll and leaves the roll perfectly cleaned with its surface in as smooth and velvety condition as originally.

As the roller 62 passes off the left end of the roll, the clutch 72 may be disengaged relative to the feed screw, whereupon the movement of the carriage is terminated. Should it be desired to repeat the cleaning operation on the roll, this may easily be accomplished by moving the carriage toward the right end of the apparatus and following the same procedure as previously explained. In some cases, it may only be necessary to perform one cleaning operation, whereas in cases where a roll has not been cleaned for a considerable time or due to the particular use to which it has been subjected, it may be necessary to repeat the operation several times before the roll is perfectly clean.

The use of the apparatus is not confined to any particular size roll, as it may be adjusted to not only take rolls of different length by varying the position of the tail stock, but may also be used with rolls of different diameters by properly adjusting the position of the cleaning instrumentalities by the hand wheel 45.

From the foregoing description, it will be apparent that the present invention provides an improved method for the cleaning of rolls such as utilized in printing presses; novel apparatus for carrying out the steps of the method; a roll cleaning method which will thoroughly clean the roll and restore it to its original condition without in any way injuring the roll surface or decreasing its diameter, thus materially increasing the life of the roll; which effectively removes any ink which has penetrated or been absorbed by the roll; an apparatus wherein a plurality of different cleaning operations may be carried on simultaneously and in proper sequence to carry out the method of my invention; and in which the process may be carried out quickly and automatically without the aid of expensive skilled labor.

It is, of course, to be understood that although I have described in detail the preferred embodiment of my invention, the invention is not to be thus limited, but only insofar as defined by the scope and spirit of the appended claims.

I claim as my invention:

1. Apparatus for the reconditioning of rolls of resilient surface characteristics comprising means for rotating the roll about its longitudinal axis, a pair of spaced idler rollers, power driven buffer means disposed between said rollers, said rollers and buffer means being supported for unitary movement axially of the roll and engaging spaced portions of the roll surface which are substantially aligned longitudinally of the roll, and means for applying a cleansing fluid to said roll.

2. Apparatus for reconditioning a roll comprising means for supporting the roll, a buffer wheel disposed in surface engagement with the surface of the roll, means for rotating said buffer wheel, means for changing the surface on said roll engaged by said buffer wheel in a direction circumferentially of said roll, means for changing the surface on said roll engaged by the buffer wheel in a direction axially of the roll, and means for supplying a stream of cleaning liquid between the roll and buffer wheel.

3. Apparatus for reconditioning a roll comprising means for rotatably supporting the roll, a buffer wheel disposed in surface engagement with the surface of the roll, means for rotating the roll and buffer wheel, means for feeding the buffer wheel in a direction axially of the roll, and means movable with the feeding movement of the buffer wheel for applying a stream of cleaning fluid to the roll during the buffing operation.

4. In apparatus of the character described, means for supporting a roll having resilient surface characteristics, means for kneading the roll surface, means for applying a cleaning fluid to the surface of the roll, and means including an idler roller of frusto-conical shape for drying the roll.

5. Reconditioning apparatus for rolls comprising means for rotatably supporting a roll, a carriage supported for movement along said roll, a container for a cleaning fluid supported below the roll for movement with the carriage, means including a pump for applying fluid from the container in a stream to the roll surface, and means carried by said carriage for successively performing reconditioning operations on the roll surface as the carriage is moved along the roll.

6. Reconditioning apparatus for rolls comprising means for rotating a roll to be reconditioned, a carriage supported for independent movement along said roll, instrumentalities carried by said carriage for successively performing reconditioning operations on the roll surface as the carriage is moved along the roll, fluid nozzle means on the carriage for directing a fluid stream onto the roll surface, means for collecting said fluid including a tank carried by and movable with said carriage, and means for supplying fluid from the tank to said fluid nozzle means.

7. Reconditioning apparatus for rolls comprising means for rotating a roll to be reconditioned, a carriage supported for independent movement

along said roll, instrumentalities carried by said carriage for successively performing reconditioning operations on the roll surface as the carriage is moved along the roll, fluid nozzle means on the carriage for directing a fluid stream onto the roll surface, a catch basin for collecting the fluid from said roll, a storage tank carried by and movable with said carriage, said tank having a gravity flow connection from the catch basin, and means for elevating fluid from the tank to said nozzle means.

8. Reconditioning apparatus for rolls comprising means for rotating a roll to be reconditioned, a carriage supported for independent movement along said roll, instrumentalities carried by said carriage for successively performing reconditioning operations on the roll surface as the carriage is moved along the roll, fluid nozzle means on the carriage for directing a fluid stream onto the roll surface, a catch basin for collecting the fluid from said roll, a storage tank carried by and movable with said carriage, said tank having a gravity flow path for fluid from the catch basin, fluid filtering means in said path, and means for elevating filtered fluid from the tank to said nozzle means.

9. Apparatus for the reconditioning of rolls of resilient surface characteristics comprising means for rotating the roll about its longitudinal axis, a pair of spaced idler presser rollers, power driven buffer means disposed between said rollers, a common carriage support for the presser rollers and buffer means, means for feeding the carriage to simultaneously move the presser rollers and buffer means longitudinally along the roll surface, and a single adjusting means for simultaneously moving the presser rollers and buffer means towards and away from the roll surface to vary their pressure thereagainst.
